Primary Examiner — Marianne Pandozzi(74) Attorney, Agent, or Firm — Renner, Otto, Boisselle & Sklar, LLP(57) CLAIM

The ornamental design for a coffee maker, as shown and described.

DESCRIPTION

FIG. 1 is a perspective view of a coffee maker showing my design.

FIG. 2 is a right side view thereof.

FIG. 3 is a left side view thereof.

FIG. 4 is a rear view thereof.

FIG. 5 is a front end view thereof.

FIG. 6 is a top end view thereof; and,

FIG. 7 is a bottom view thereof.

The broken lines depict portion of the coffee maker that form no part of the claimed design.
